FRANCIS HIGHT, OF WINCHESTER, MASSACHUSETTS, ASSIGNOR TO PERRY MASON COMPANY, OF BOSTON, MASSACHUSETTS, A CORPORATION OF MASSACHUSETTS.

CARD OR PICTURE SUPPORT.

1,111,458.

Specification of Letters Patent. Patented Sept. 22, 1914.

Application filed March 5, 1912. Serial No. 681,719.

To all whom it may concern:

Be it known that I, FRANCIS HIGHT, a citizen of the United States, and resident of Winchester, in the county of Middlesex and State of Massachusetts, have invented certain new and useful Improvements in Card or Picture Supports, of which the following is a specification.

This invention has for its object to provide a holder which, though particularly useful for a calendar, may be employed for pictures, advertisements, or reading or pictorial matter of all kinds.

The invention consists of a frame, having hinged thereto a clamp comprising spring members, in consequence of which the clamp forms a supporting leg to hold the frame in an upright position, or forms an attaching member by which the frame may be suspended from or clamped to any convenient support.

On the drawings.—Figure 1 is a perspective view of a holder embodying the invention. Fig. 2 represents a rear elevation of the same. Fig. 3 represents a side elevation of the holder attached to a shelf. Figs. 4 and 5 show different ways in which the frame may be held by the clamp. Fig. 6 illustrates the blank which, when bent into shape, constitutes the clamp.

The frame is illustrated as consisting of a body formed of a metallic sheet a and having on two opposite side edges internal flanges a' separated far enough from the body to permit the insertion of one or more detachable or removable sheets or cards b . A third edge of the body (which may be called the bottom edge for convenience) has a flange a^2 , while the fourth edge of the body (called for convenience the top or upper edge) is formed with eyes or hinge members a^3 , which as shown in Fig. 3, are bent rearwardly out of the plane of the card-holding space, so as not to interfere with the insertion or removal of the cards or sheets b . Preferably the body is square in front elevation and the cards or sheets are likewise square, so that the latter may be inserted downward or sidewise into the frame according to the position of the latter, and be held in proper position to be read or observed. So far as other features of the invention are concerned, however, the frame and the cards may be of other shapes and 55 may be as ornamental as fancy dictates.

Hinged to the top edge of the frame is a clamp c , formed for convenience from a single blank of resilient metal as shown in Fig. 6. The blank is bent on a transverse line to provide two spring clamp members c' c^2 , of which the latter is long enough to constitute a leg or support, and hold the frame in an inclined upright position as illustrated in Fig. 1. The ends of the clamp members are divergent, so that the end of the member c' acts as a stop to engage the frame or the cards therein and limit the inward movement of the supporting member c^2 , and so that the clamp may be easily engaged with a convenient projection.

Projecting from the blank are two ears or lugs c^3 , which, when the blank is bent as described, are doubled along longitudinal lines to constitute pintles or hinge members for engagement with the eyes or hinge members a^3 . Preferably the body portions of the spring members are curved as shown in Fig. 3, so that they form a hook, and thus permit the frame to be suspended from a rod d or other convenient hanger as illustrated in Fig. 4. Some typewriting machines are equipped in the front portion above the keys with such a rod, and the holder may be hung thereon. In other typewriting machines there is an upright form of bar of the general character of that illustrated conventionally in Fig. 5, with which the clamp members may be engaged. Thus to machines of either type the holder may be easily attached to present the cards or sheets for the inspection of the operator. The hinged connection between the clamp and the frame permits the frame to be swung to any desirable angle.

Without attempting to set forth the manifold uses to which the holder may be put, I may state that it may be employed for advertisements, photographs, pictures, or for any written or printed matter to which it is desirable to refer, so that, while I call it a calendar holder, the term has no limiting significance. The holder may be stood upon a desk or table, may be clamped to any horizontal or vertical projection, or may be suspended from any convenient support. The clamp member c^2 may be provided with a keyhole slot as at c^4 to permit it to be hung on the head of a tack or nail.

In lieu of making the frame of a single sheet of metal or other material, it may be

formed in other ways which will readily suggest themselves.

As shown by the drawings, the sheet *a* is cut away to form a central opening which is 5 covered by the card or cards *b* when the latter are attached. When no card is attached, the clamping member *c'* may extend through the opening and thus minimize the space into which the article may be folded 10 when not in use, as for example when a plurality of the holders are packed for shipment. According to commercial customs the holders would be produced by manufacturers of sheet metal articles, and the cards 15 would be produced by a printer, and the holders would be shipped without the cards. It is desirable, therefore, that the holders be adapted to be folded into as compact form as possible, and this is brought about 20 by forming the holder with the aforesaid opening through which the clamping members *c'* may extend. When the card is placed in the holder, it is adapted to be engaged by the free end of the member *c'*, and thus act 25 to determine the propping position of the prop member *c²*.

Having thus explained the nature of my said invention and described a way of making and using the same, although without attempting to set forth all of the forms 30 in which it may be made or all of the modes of its use, what I claim is:

An article of manufacture comprising a card frame having means for detachably holding a card by the edges, a prop member 35 hinged to said frame, and a clamping member carried by said prop member, said two members being adapted to coöperate to clamp an interposed support, said frame having an opening adapted to receive one 40 of said members when no card is attached, to minimize the bulk of the article for storage, said one of said members being adapted to bear against the back of an attached card when said prop member is in 45 propping position.

In testimony whereof I have affixed my signature, in presence of two witnesses.

FRANCIS HIGHT.
